CLAIM

The ornamental design for a water bottle, as shown and described.

DESCRIPTION

FIG. 1 is a front, top, and left perspective view of a water bottle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof; and,

FIG. 9 is an enlarged view of the portion indicated with the number 9 in FIG. 2.

The dot-dash lines in the drawings depict the boundaries of the enlarged views and form no part of the claimed design.

1 Claim, 9 Drawing Sheets
